DESIGN FOR A BOTTLE

Tobias Miller, New York, N. Y.

Application March 22, 1934, Serial No. 51,146

Term of patent 7 years

To all whom it may concern:

Be it known that I, TOBIAS MILLER, a citizen of the United States, residing at New York city, in the county and State of New York, have invented a new, original, and ornamental Design for a Bottle, of which the following is a specification, reference being had to the accompanying drawing forming a part thereof.

I claim:

The ornamental design for a bottle as shown.

TOBIAS MILLER.
